FIRE TUBE HEAT FLOW REGULATORS
Ralph S. Evans, 4711 NW, 170th St., Miami, Fla.
Filed Nov. 20, 1962, Ser. No. 238,932
7 Claims. (Cl. 110—97)

This invention relates to boiler construction and is more particularly directed to fire tube heat flow regulators for boilers.

A principal object of the present invention is to provide heat flow regulators for fire tube boilers that increase the efficiency of the boilers when firing at less than its full capacity.

Another object of the present invention is to provide heat flow regulators for fire tube boilers that prevent the hot combustion gases from flowing through the upper banks of fire tubes but compels the gases to be diverted so as to pass through all of the fire tubes.

A further object of the present invention is to provide heat flow regulators for each row or group of rows of tubes of a fire tube boiler wherein the regulators are provided with valve plates of various thicknesses, the plates decreasing in weight in the direction of the lower group of valve plates to direct the flow of gases through the lower fire tubes at low capacity operation.

A further object of the present invention is to provide heat flow regulators for each tube of a fire tube boiler, which regulators are simple in construction, inexpensive in cost, readily positioned in the fire tubes and most effective to raise the efficiency of the boiler when firing at low capacity.

A still further object of the present invention is to provide a fire tube boiler with a plurality of heat flow regulators that permit the purging and cleaning of the fire tubes and permit some flow of combustion gases therethrough even when the boiler is firing at its lowest capacity.

With these and other objects in view, the invention will be best understood from a consideration of the following detailed description taken in connection with the accompanying drawing forming a part of this specification, with the understanding, however, that the invention is not confined to any strict conformity with the showing of the drawing but may be changed or modified so long as such changes or modifications mark no material departure from the salient features of the invention as expressed in the appended claims.

In the drawing:

FIGURE 1 is a cross sectional view of a fire tube boiler embodying my invention.

FIGURE 2 is a detailed fragmentary sectional view of my heat flow regulators shown in position on a fire tube.

FIGURE 3 is a front elevational view thereof.

FIGURE 4 is an exploded perspective view of the fire tube regulator.

FIGURE 5 is a fragmentary side elevational view of the valve plates 23 showing the variation in thicknesses of the various heat flow regulators.

Referring to the drawing wherein like numerals are used to designate similar parts throughout the several views, the number 10 refers to a fire tube boiler of conventional construction and to which have been added my heat flow regulators 11.

The fire tube boiler 10 consists of the usual outer walls to form a combustion chamber 12, passageway for combustion gases 13, heat exchange chamber 14 and flue or stack 15 for the discharge of the combustion gases.

Mounted on a front wall 16 of the boiler 10 is a burner 37 which directs the air and oil or gas to mix and become ignited in the combustion chamber 12. The hot combustion gases will flow along the passageway 13 and into some of the many fire tubes 17 which extend between front and rear walls 18 and 19 respectively, which with

2

top and bottom walls 30 and 31 form the water chamber of the boiler 10. The fire tubes 17 are arranged in a vertical bank of horizontal rows of fire tubes 17 so that a maximum rate of heat exchange between the hot combustion gases and the water in the water chamber is effected.

The boilers 10 are constructed to provide maximum efficiency at a high rate of heat exchange or at high fire as it is known in the art. All of the fire tubes 17 receive approximately the same amount of combustion gases and therefore transmit to the water approximately the same amount of heat or B.t.u.'s. However, when the boiler is operating at below high fire, the draft at the burner is reduced and the total amount of combustion gases is now less than at high fire. The passage 13 will now have a smaller volume of combustion gases passing therethrough than when the boiler 10 was firing at high fire. However, the hot combustion gases will rise to the upper portion of the passage 13 thereby causing a greater proportion of the combustion gases to flow through the upper horizontal rows of fire tubes 17 while the lower rows of fire tubes 17 will receive a very small proportion of the total combustion gases. This condition, of course, reduces the efficiency of the boiler inasmuch as the combustion gases passing through the upper fire tubes 17 will enter the stack 15 at a higher temperature than the combustion gases passing through the lower fire tubes 17.

The function of the instant devices or heat flow regulators 11 is to provide for the passing of approximately equal flows or volumes of combustion gases through all of the fire tubes 17 at all conditions of firing from high fire to low fire. The heat flow regulators 11 which are mounted at the discharge end of each of the fire tubes 17 consist of a tubular body portion 20 of the same diameter as that of the fire tubes 17. A plurality of symmetrically disposed seating prongs 21 are welded or otherwise secured to the inner surface of the tubular body portion 20 and extending beyond the inner edge thereof. Since the tubular body portion is of the same diameter as the fire tubes 17, the prongs 21 will fit snugly in the fire tubes 17 to retain the heat flow regulators 11 securely in position on the discharge end of the fire tubes 17 as best shown by FIGURE 2.

At the upper forward edge of the tubular body portion 20 is a hinge lug 22 on which a flap valve 23 is pivotally mounted. The flap valve 23 is provided with a pair of hinge lugs 24 which lie on either side of the hinge lug 22 and in alignment therewith to receive the hinge pin 25 for pivotal movement of the flap valve 23. A cotter pin 27 secures the pivot pin 25 on the lugs 22 and 24. The flap valve 23 is a gravity actuated valve normally in a closed position as shown by FIGURE 2. However, the valve plate 23 is oval at its lower portion rather than circular as is its upper portion thereby providing an opening 26 for the minimal flow of combustion gases when the valve 23 is in its closed position. The opening 26 which is at the lower portion of the fire tubes 17 permits a flow of gases at all time, the opening enlarging in proportion to the volume of flow of combustion gases.

It is to be noted that the flap valves 23 are all of the same shape and configuration except however, the thickness of the plates 23. As best shown by FIGURE 5, the valve plate 23 designated by the letter A is the thickest and heaviest plate valve mounted on the top row of the fire tubes 17. The valve plates B, C, D and E which are progressively thinner and lighter are mounted on the consecutively lower rows of the fire tubes 17.

The opening 26 being positioned at the lower portion of the fire tubes 17 permits blowing combustion products, grime, etc. out of the fire tubes 17 to clean same. Also, before firing the boiler 10 and before turning on the fuel in a gas fired boiler, the burner 37 is actuated to

blow air only through the combustion chamber 12 and fire tubes 17 to purge the area of any dangerous gases that may have accumulated therein while the boiler 10 was not in use. To start the firing before these gases are purged may result in an explosion in the boiler.

When the fire tube boiler 10 is firing at full draft or its maximum capacity all of the flap valves 23 will be swung to their maximum opening. Combustion gases will be flowing through all of the fire tubes and the boiler will be firing to provide a maximum heat exchange. As the draft is decreased, the volume flow of combustion gases will decrease. Under these conditions in the conventional fire tube boiler, the hot combustion gases will rise in the chamber 13 and flow only through the upper fire tubes 17 while little or none of the combustion gases will flow through the lower fire tubes 17. This condition reduces the efficiency of the boiler 10 since only a portion of the fire tubes 17 are being utilized and the total amount of heat transmitted to the water will be less than if all the fire tubes were being used. In the boiler 10, the combustion gases will not be flowing in sufficient volume to maintain the heavier valve plates 23 of the upper fire tubes 17 in a completely open condition but will be only partially open thereby causing the combustion gases to flow through the lower fire tubes 17 that have the lighter flap valve plates 23. As the draft is decreased further, the upper and heavier flap valves 23 will come to a closed condition allowing only a minimal flow of combustion gases therethrough. The lower flap valves 23 will be open to a greater extent in the direction of the bottom fire tubes 17. This compels the combustion gases that tend to rise in the boiler 10 to be directed so as to flow through all of the fire tubes and thereby maintain the heat exchange at its highest efficiency at all stages of draft, from a maximum draft when all the flap valves 23 are open to a minimum draft when all of the flap valves 23 are closed.

My heat flow regulators 23 are especially useful in those boilers which have been converted from oil burning boilers to gas burning boilers, the reason being that the combustion chamber for oil burning boilers is larger than that of the gas burning boiler. When the converted boiler is being used at full capacity its combustion chamber is still too large for efficient heat exchange. However, with the use of applicant's heat flow regulators 23, the combustion gases will be evenly distributed among all the fire tubes as in the boiler 10 when used at below high fire.

What I claim as new and desire to secure by Letters Patent of the United States is:

1. In a fire tube boiler having a plurality of fire tubes, each of said fire tubes having an inlet and an outlet, a fire tube heat flow regulator comprising a body member, means securing said body member to said outlet of said fire tube, a valve plate, pivot means yieldingly mounting said valve plate on said body member in a normally closed position, said valve plate swinging in a direction away from said fire tube to an open position upon sufficient pressure being exerted by combustion gases and being smaller than said fire tube whereby an opening is formed with said valve plate in said closed position to permit a restricted flow of combustion gases through said fire tube.

2. In a fire tube boiler having a plurality of fire tubes, each of said fire tubes having an inlet and an outlet, a fire tube heat flow regulator comprising a body member, removable means securing said body member to said outlet of said fire tube, a valve plate, pivot means mounted on an upper portion of said body member and said valve plate pivotally mounting said valve plate to said body member and yieldingly retaining said valve plate against said body member in a closed position, said valve plate being swung to its open position by sufficient pressure exerted by combustion gases in said fire tube and being slotted at its lower portion whereby in its normally

closed position said valve plate permits a limited flow of combustion gases.

3. In a fire tube boiler having a plurality of fire tubes, each of said fire tubes having an inlet and an outlet, a plurality of fire tube heat flow regulators each comprising a cylindrical body member having substantially the same diameter as said fire tubes, removable means securing said body members to said outlets of said fire tubes, a plurality of valve plates, pivot means mounted on an upper portion of each of said valve plates and said body members pivotally mounting each of said valve plates to said body members and normally retaining said valve plates in a closed position, said valve plates swinging to an open position upon sufficient pressure being exerted by combustion gases flowing through said fire tubes and each valve plate having a lower portion terminating in spaced relation to the lower edge of said body members forming an opening for the flow of restricted combustion gases therethrough when said valve plates are in a closed position upon the pressure of combustion gases being insufficient to open said valve plates.

4. In a fire tube boiler having a plurality of horizontally disposed fire tubes mounted in a vertical tier, each of said fire tubes having an inlet and an outlet, a plurality of fire tube heat flow regulators each comprising a cylindrical body member having substantially the same diameter as said fire tubes, a plurality of prongs secured to the inner surface of said cylindrical body member and extending outwardly of said cylindrical body member, said prongs being slidably received by said outlets of said fire tubes for removably securing said body members to said fire tubes, a plurality of valve plates, pivot means mounted on an upper portion of each of said valve plates and said body members pivotally mounting each of said valve plates to said body members and normally retaining said valve plates in a closed position, said valve plates swinging to an open position upon sufficient pressure being exerted by combustion gases flowing through said fire tubes and each of said fire plates having an upper portion engaging said body members and a lower portion terminating in spaced relation to the lower edge of said body members forming an opening for a restricted flow of combustion gases therethrough when said valve plates are in a closed position upon the pressure of combustion gases being insufficient to open said valve plates.

5. In a fire tube boiler having a vertical row of horizontally disposed fire tubes, said fire tubes each having an inlet and an outlet, a combustion chamber communicating with said inlets of said fire tubes, a plurality of pressure operated valve means mounted on said outlets of said fire tubes, said pressure operated valve means requiring decreasingly less pressure from the upper to the lower fire tubes to open said valve means, and openings in said valve means permitting a restricted flow of combustion gases from said combustion chambers to pass through said fire tubes when there is sufficient pressure exerted by said combustion gases to open said valve means and said valve means are in a closed position.

6. In a fire tube boiler having horizontally disposed fire tubes, said fire tubes each having an inlet and an outlet, a plurality of fire tube heat flow regulators each comprising a cylindrical body member having substantially the same diameter as said fire tubes, removable means securing said body members to said outlets of said fire tubes, a plurality of valve plates, pivot means mounted on an upper portion of each of said valve plates and said body members pivotally mounting each of said valve plates to said body members and normally retaining said valve plates in a closed position, said valve plates swinging to an open position upon sufficient pressure being exerted by combustion gases flowing through said fire tubes and each having a lower portion terminating in spaced relation to the lower edge of said body members forming an opening for a restricted flow of combustion gases therethrough when said valve plates

are in a closed position upon the pressure of combustion gases being insufficient to open said valve plates, and said valve plates of said upper fire tubes requiring a greater force to swing to an open position than said valve plates of said lower fire tubes.

7. In a fire tube boiler having a plurality of horizontally disposed fire tubes mounted in a vertical tier, said fire tubes each having an inlet and an outlet, a plurality of fire tube heat flow regulators each comprising a cylindrical body member having substantially the same diameter as said fire tubes, a plurality of prongs secured to the inner surface of said cylindrical body member and extending outwardly of said cylindrical body member, said prongs being slidably received by said outlets of said fire tubes for removably securing said body members to said fire tubes, a plurality of valve plates, pivot means mounted on an upper portion of each of said valve plates and said body members pivotally mounting each of said valve plates to said body members and normally retaining said valve plates in a closed position, said valve plates swinging to an open position upon sufficient pressure being exerted by combustion gases flowing through said fire tubes and said valve plates having an upper portion engaging said body members and a lower portion termi-

nating in spaced relation to the lower edge of said body members forming an opening for the passage of combustion gases therethrough when said valve plates are in a closed position, said valve plates of said upper fire tubes being lighter in weight than said valve plates of said lower fire tubes whereby a greater pressure of combustion gases are required to open the upper valve plates than the lower valve plates.
